(57) **CLAIM**

I claim the ornamental design for a trim and connector track for a truck or trailer deck, as shown and described.

DESCRIPTION

FIG. 1 is right side elevation view of the trim and connector track for a truck deck;

FIG. 2 is a left side elevation view of the trim and connector track for a truck deck shown in FIG. 1;

FIG. 3 is a top plan view of the trim and connector track for a truck deck shown in FIG. 1;

FIG. 4 is a front elevation view of the trim and connector track for a truck deck shown in FIG. 1;

FIG. 5 is a bottom plan view of the trim and connector track for a truck deck shown in FIG. 1;

FIG. 6 is a rear elevation view of the trim and connector track for a truck deck shown in FIG. 1; and,

FIG. 7 is a perspective view of the trim and connector track for a truck deck shown in FIG. 1.

In the drawings, the broken lines depict portions of the article that form no part of the claimed design.
